UNITED STATES PATENT OFFICE.

ALEXANDER WINTON AND HAROLD B. ANDERSON, OF CLEVELAND, OHIO, ASSIGNORS TO THE WINTON MOTOR CARRIAGE COMPANY, OF CLEVELAND, OHIO.

VALVE-ACTUATING MECHANISM FOR EXPLOSIVE-ENGINES.

No. 919,104.

Specification of Letters Patent.

Patented April 20, 1909.

Application filed September 8, 1906. Serial No. 333,810.

To all whom it may concern:

Be it known that we, ALEXANDER WINTON and HAROLD B. ANDERSON, citizens of the United States, residing at Cleveland, in the 5 county of Cuyahoga and State of Ohio, have invented certain new and useful Improvements in Valve-Actuating Mechanism for Explosive-Engines, of which the following is a specification, reference being had therein 10 to the accompanying drawing.

This invention relates to improvements in valve actuating mechanism for explosive engines the primary object of which is to so arrange and construct the parts that the valves 15 and their coöperating parts can be readily and independently removed, and therefore readily accessible for inspection, repair or substitution.

In the accompanying drawing Figure 1 is 20 a side elevation of a vertically arranged explosive engine, partly in section, with the present improvement applied thereto. Fig. 2 is an enlarged side elevation (partly in section) of the outer ends of the valve stems 25 and the adjacent coöperating parts. Fig. 3 is a detached side view of the valve stem yoke. Fig. 4 is a top plan view (partly in section) of the valve stem yoke, and the parts carried by and coöperating therewith.

30 The present invention is here shown applied to a multiple cylinder engine, and is especially intended for such use, though it is capable of use upon a single cylinder engine; and it is shown applied to a vertically arranged engine, but the engine may be in any 35 desired position without affecting or departing from the spirit and scope of the invention.

Fig. 1 illustrates a two cylinder engine, and 40 1 indicates the explosive ends of the cylinders; 2 the inlet valve and 3 the exhaust valve. The valves 2 and 3 are placed in position and removable through the screw-plug closed openings 4 made in the end wall 5 opposite and in a line with the reciprocating movement of the valves. The means for holding the valves normally to their seats consists in providing the projecting valve stems 6 with transverse readily removable 45 pins 7. A valve stem yoke 8 has its looped ends 9 straddling and passing around the valve stems 6 and provided at its under side with the recesses 10 which receive the projecting ends of the pins 6. These recesses 50 have end walls 10 closing their outer ends,

and these walls serve to hold the pins 6 in place in the valve stems. A spring containing barrel or thimble 11 is provided with trunnions 12 projecting from opposite sides and resting in the recesses 13 of the yoke 8, 60 whereby the yoke may work in respect to the thimble as the valves are reciprocated. Placed in this spring thimble 14 is a spiral spring 15 with one end resting against the bottom of the thimble and its upper end 65 resting against the under side of the casing 1. Projecting from this casing is a pin 16 which passes through the spring and prevents the spring from buckling, or lateral movement under the influence of the combined tilting 70 and reciprocating movement of the yoke 8 as the valves are worked back and forth.

A cam shaft 17 is placed below the valves 2 and 3 and is provided with the two sets of cams 18 and 19, the former for opening the 75 exhaust valves 3 and the latter for opening the inlet valves 2. These valves are kept closed through the action of the springs 15 through the medium of the yokes. When the inlet valve 2 is forced open by its cam 19 (as shown in Fig. 1) one end of the yoke 8 is moved up against the expanding tension of the spring 15, while the pin 7 of the exhaust valve forms a fulcrum for the yoke. Likewise, when the exhaust valve 3 is 80 opened by its cam 18, the exhaust valve end of the yoke is raised while the opposite end thereof is fulcrumed on the pin of the inlet valve stem. From the foregoing it will be observed that a single spring is utilized for 85 normally closing both the inlet and exhaust valves, and certain advantages arise in the assembling and removal of the parts which 90 will be pointed out hereinafter. Reciprocating heads or pistons 20 are situated between the said cams and valve stems, and they move in suitable housings 21. Journaled in the lower ends of these pistons are rollers 22 with which the cams engage. These pistons 20 are provided with projecting 95 stems 23, and these stems carry adjustable heads 24 which engage the lower ends of the valve stems when the pistons are forced upward by their respective cams. Placed between the upper ends of the pistons 20 and the tops of their housings 21 are suitable 100 expanding springs 25 which serve to normally force the pistons downward or inward. For the purpose of keeping the pistons 105 from turning in their housings they are 110

110

provided with longitudinal grooves 26 into which project the pins 27 and placed between the outer projecting ends or heads of these pins is a suitable member 20 which 5 holds them in place.

Attention is directed to the casing 29 of the cam-shaft 17 and the removable bearings 30, which casing is made of a diameter sufficient to permit the cam-shaft and its 10 cams to be removed endwise, when the bearings 30 are removed. This arrangement permits the cam-shaft with the cams intact to be readily and quickly removed without disturbing any other part of the mechanism. 15 Should it be desired to remove any one of the valves, it is only necessary to lift that end of the yoke to unseat the pin 7, push the pin endwise, and the valve can be removed through its screw-plug opening 4 or 5. If 20 desired both valves can in the same manner be removed at the same time, and are readily accessible for that purpose. Also the housings 21 are readily accessible for removal together with their pistons without 25 disturbing any other part of the mechanism.

Having thus described the invention, what we claim and desire to secure by Letters Patent is—

30 1. The combination of two reciprocating valves having valve stems projecting in the same direction, removable pins passing through said stems, a spring yoke having its ends projecting at each side of said valve 35 stems and engaging said pins, the yoke constructed to hold the pins in place and a spring holding the yoke in engagement with the pins.

2. The combination of two valves having 40 stems projecting in the same direction, removable pins passing through the stems, a spring yoke having its ends extending at each side of the stems and provided with recesses constructed to hold the pins against 45 endwise removal, and a spring holding the yoke in engagement with the pins.

3. The combination of a reciprocating valve having a stem, a removable pin passing through its stem, and a spring yoke having 50 a recess constructed to receive and prevent the endwise movement of the pin while in engagement therewith.

4. The combination of a reciprocating valve having a projecting stem, a spring 55 holding the valve closed, a reciprocating piston having an adjustable head adapted to engage said valve stem, and means for moving the piston, the parts constructed for the purpose described.

60 5. The combination with an engine having two valves, the stems of which extend in the same direction, a yoke pivotally connected to the stems, a housing within the yoke intermediate the valve stems and having trunnions resting in recesses within the yoke, a

spring within the housing and having its upper end bearing against a stationary part of the engine.

6. The combination with an engine having two valves, the stems of which extend in the same direction, a yoke pivotally connected to the stems, a housing within the yoke intermediate the valve stems and having trunnions resting in recesses within the yoke, a spring within the housing and having its upper end bearing against the stationary part of the engine, and a pin carried by the engine and extending through the coils of the spring into the housing. 75

7. The combination with two valves having stems projecting in the same direction, pins passing through stems, a yoke having its ends surrounding the stems and the lower faces thereof having recesses constructed to receive the pins, and means for holding the 85 yoke in engagement with the pins.

8. The combination with an engine having two valves, the stems of which extend in the same direction, a yoke having recesses in its lower face, pins extending through the stems 90 and entering the recesses in the yoke, and a spring-carrying member having trunnions resting in recesses within the upper face of the yoke.

9. The combination with an engine having two valves, the stems of which extend in the same direction, a yoke having recesses in its lower face, removable pins carried by the stems and resting in the recesses and held 95 against longitudinal movement thereby, a housing within the yoke intermediate the valve stems and having trunnions resting in recesses within the yoke, and a spring within the housing and bearing against the stationary part of the engine. 100

10. The combination with an engine having two valves, the stems of which extend in the same direction, a yoke pivotally connected thereto, a housing pivotally mounted within the yoke intermediate the valve 110 stems, a spring within the housing and having its upper end bearing against a stationary part of the engine, and a pin carried by the engine and extending through the coils of the spring and into the housing. 105

11. The combination with an engine having two valves, the stems of which extend in the same direction, a yoke pivotally connected thereto, a coil spring bearing against the yoke and having its upper end in engagement 120 with a stationary part of the engine, and a pin carried by the engine and extending through the coils of the spring.

12. The combination with two valves having stems projecting in the same direction, pins passing through the stems, a yoke having its ends provided with recesses in their lower faces and constructed to receive the pins, and means for holding the yoke in engagement with the pins. 125

13. The combination with two valves having stems projecting in the same direction, pins removably passing through the stems, a yoke having its ends extending on both sides 5 of the stems and said ends having recesses adapted to receive said pins and lock them in the valve stems, a housing within the yoke, trunnions carried by the housing and resting in recesses carried by the upper face of the 10 yoke, a spring within the housing and having its upper end bearing against a stationary part of the engine, and a pin carried by the engine and extending through the coils of the springs and into the housing.
- 15 14. The combination with two valves having stems projecting in the same direction, a yoke composed of end portions extending on opposite sides of the stems and pivotally connected to the stems, the ends of said stem 20 connected, said yoke having a central enlarged rounded side, a member pivotally mounted in said yoke within the central en-

larged portion, and a spring resting against the member and bearing against a stationary part of the engine.

15. A valve mechanism comprising a yoke composed of arms having parallel outer ends, means connecting said ends, valve stems extending between said ends and pivotally connected thereto, the central portion of said yoke enlarged outwardly and scooped downwardly, a housing within said enlarged portion of the yoke and having trunnions pivotally supported by the yoke, and a spring within the housing and bearing against a stationary part of the engine.

In testimony whereof we affix our signatures in presence of two witnesses.
